UNITED STATES PATENT OFFICE.

THEODORE ERNST, OF BAYFIELD, WISCONSIN.

COMBINATION CONVERTIBLE NURSERY CHAIR AND TABLE.

1,277,888.

Specification of Letters Patent. Patented Sept. 3, 1918.

Application filed May 9, 1918. Serial No. 233,458.

To all whom it may concern:

Be it known that I, THEODORE ERNST, a citizen of the United States, residing at Bayfield, in the county of Bayfield, State of Wisconsin, have invented a new and useful Improved Combination Convertible Nursery Chair and Table; and I do hereby declare the following to be a full, clear, and exact description of the invention, such as will enable others skilled in the art to which it appertains to make and use the same.

This invention relates to an improved combination convertible nursery or high chair and table, and one of the objects of the invention is to provide a simple, improved and efficient device of this kind, comprising but few parts, consequently affording a practical device.

A further object of the invention is the provision of a device of this kind, which may be manufactured at a small cost and sold at a reasonable profit.

A further object of the invention is to provide a combination convertible nursery chair and table consisting of an upper section and a lower section hingedly united, whereby the lower section may be inverted in order to be used or employed as a table.

A further object of the invention is to provide the adjacent ends of the sections of the rear legs of the chair with wheels or rollers, whereby when the lower section of the chair is inverted the two sections will be supported on the wheels, so that the device may be easily portable from one place to another.

A further object of the invention is the provision of tensioning means of holding the chair section in a super-imposed position on the table section, or the table section inverted and in a position adjacent the chair section.

A further object of the invention is the provision of means on the table section, such as a chair rung, to be engaged by the wheels on the legs of the chair section to limit the chair section in its super-imposed position.

A further object of the invention is the provision of means, such as sliding balls or spherical members on the chair section, to

be played with, in order to render amusement for the baby.

In practical fields the details of construction may necessitate alterations falling within the scope of what is claimed.

The invention comprises further features and combination of parts as hereinafter set forth shown in the drawings and claimed.

In the drawings:—

Figure 1 is a view in elevation of the combination nursery chair and table, showing the table section inverted.

Fig. 2 is a sectional view through Fig. 1.

Fig. 3 is a view in front elevation of the combination nursery chair and table, showing the chair section super-imposed on the table section.

Fig. 4 is a sectional view on line 4—4 of Fig. 3.

Referring more especially to the drawings, 1 and 2 designate the two sections of the combination chair and table. The section 1 comprises the four legs 3, which form supports for the legs 4 and 5 of the chair section, when superimposed on the section 1, whereby the device may be utilized as a high chair. The front legs of the section 1 are hingedly connected as shown at 6 to the front legs 4 of the chair section, whereby the front legs 4 may be extended axially with the front legs 3 of the section 1, or be collapsed and the section 1 inverted, whereby said section 1 may be used as a table with the chair section adjacent thereto, as shown in Figs. 1 and 2 clearly. The upper parts of the legs 3 of the section 1 are connected and braced by means of the rungs 7. The lower parts of the legs 3 are connected and reinforced by means of a table top 8, which has flanges 9 on three of its marginal edges. These flanges 9 also are connected to the legs 3 to additionally reinforce said legs.

The upper parts of the rear legs 3 of the section 1 are connected by the shaft or rung 10. The chair section 2 additionally comprises the chair seat 11, a conventional form of back 12, and the arms, which comprise the arm rests 13 and the substantially perpendicular stays or supports 14 for the rests.

The forward ends of the arm rests are provided with slots 15 for the reception of the table section 16 for the chair. A pin 17 passes through the forks of one of the slotted ends, to secure the table section pivotally in place. A spring catch 17^a is carried by the forks of the opposite slotted end of the other arm rest, to engage and hold the table section detachably in position. In fact by 5 means of the spring catch one end of the table section may be quickly disconnected from the slotted end of the arm rest, to permit the occupant of the chair to be removed. An arched shaped rod 18 is fastened on the 10 table section 16, as shown at 18^a, and mounted slidably on the rod are balls or spherical members 19 which may be moved backward and forward on the rods for amusing the baby. The chair section 2 is provided with 15 a foot rest 20 which consists of the foot board 21 and the end pieces 22. Extensions 23 of the end pieces 22 are pivoted by means of pins or screws 24 to the front legs 4 of the chair section. The rear extremities of said 20 extensions 23 engage under the rung 25, which is fastened securely in any suitable manner to the rear faces of the legs 4, whereby the foot rest may be supported in a horizontal position. By so mounting the foot rest it may be moved upwardly on its pivots 25 as shown in dotted lines in Fig. 1, whereby the rest may be supported and held out of position by the rung 25, the lower ends of the legs 5 of the chair section being connected by a rung 26, thereby bracing the legs 5.

The upper parts of the legs 5 adjacent where they connect to the chair seat 11 are connected by a rung or shaft 26^a, and 40 pivoted upon this rung or shaft are the arms or members 26^b. The lower ends of the arms or members 26^b are connected by a shaft or rung 26^c, the extremities of which carry the wheels or rollers 27. When 45 the chair section 2 is super-imposed on the section 1 as shown clearly in Figs. 3 and 4, the wheels 27 are idle, but the lower ends of the legs 5 will rest on the upper ends of the rear legs 3 of the section 1, thereby supporting 50 the chair section. The ends of the rung or shaft 10 have journaled thereon rollers or wheels 29, which when the table section 1 is inverted, as shown in Figs. 1 and 2, the wheels 29, and also the wheels 27 55 are designed to engage the floor or the like, consequently supporting the front legs of both sections up off the flooring. The lower parts of the arms or members 26^b are provided with shoulders 26^d, designed to engage the rung 10, of the rear legs 3 of the section 1, to hold the chair section 2 super-imposed on the chair section 1. A pair of springs 30 are connected to one of the rungs 7 of the chair section 1. The other

ends of the springs 30 are connected at 30^a 61 to the arms or members 26^b, so as to hold the shoulders 26^d in engagement with the rung 10, when the chair section 2 is super imposed on the chair section 1. When it is desired to invert the chair section 1, so as 71 to employ the table 8, the shoulders 26^d are disengaged from the rung 10. After disengaging the shoulders from the rung 10 the section 1 may be inverted to the position shown in Figs. 1 and 2. The springs 30 are 78 again put under tension, holding the two sections as in Figs. 1 and 2, and also the arms or members in contact with the rung 26. The end portions 26^e of the arms or members 26^b engage the under face of the 80 chair seat 11, in order to relieve excessive pressure on the rung 26.

The invention having been set forth what is claimed as new and useful is:—

1. In a device as set forth, a chair section 85 and a base section, the adjacent ends of the forward legs of both sections being hingedly united, the adjacent ends of the rear legs of both sections adapted to disengageably abut arms, arms pivoted to the rear 90 part of the chair section, spring means for said arms, the free ends of said arms and the upper ends of the rear legs of the base section having wheels to support the front legs of both sections spaced upwardly from 95 the floor, when the base section is inverted.

2. In a device as set forth, a chair section and a base section, the adjacent ends of the forward legs of both sections being hingedly united, the adjacent ends of the rear 100 legs of both sections adapted to disengageably abut arms, arms pivoted to the rear part of the chair sections, the free ends of said arms and the upper ends of the rear legs of the base section having wheels to support the 10 front legs of both sections spaced upwardly from the floor, when the base section is inverted, a rung connecting the upper ends of the rear legs of said base section, said arms having shoulders to engage the rung 11 connecting the upper ends of the rear legs of the base section, to hold the chair sections super-imposed on the base section.

3. In a device as set forth, a chair section and a base section, the adjacent ends of the 11 forward legs of both sections being hingedly united, the adjacent ends of the rear legs of both sections adapted to disengageably abut, arms pivoted to the rear part of the chair sections, the free ends of said arms 12 and the upper ends of the rear legs of the base section having wheels to support the front legs of both sections spaced upwardly from the floor, when the base section is inverted, a rung connecting the upper ends 12 of the rear legs of said base section, said arms having shoulders to engage the rung connecting the upper ends of the rear legs

of the base section, to hold the chair sections super-imposed on the base section, spring means connected to the forward part of the base section and to said arms or members, to hold the shoulder in engagement with the rung, or the base section inverted, and means for limiting said arms or members.

In testimony whereof I have signed my name to this specification in the presence of two subscribing witnesses.

THEODORE ERNST.
